Aubrey A. Adcock.
BY *Arthur Deacon*
ATTORNEY.

UNITED STATES PATENT OFFICE.

AUBREY A. ADCOCK, OF KANSAS CITY, MISSOURI.

OIL BURNER.

Application filed December 13, 1923. Serial No. 680,382.

To all whom it may concern:

Be it known that I, AUBREY A. ADCOCK, a citizen of the United States, residing at Kansas City, in the county of Jackson and 5 State of Missouri, have invented certain new and useful Improvements in Oil Burners; and I do declare the following to be a full, clear, and exact description of the invention, such as will enable others skilled in 10 the art to which it appertains to make and use the same, reference being had to the accompanying drawings, and to the figures of reference marked thereon, which form a part of this specification.

15 This invention relates to an oil burning system including a feed tank and a burner for vaporizing hydrocarbon oils, preparatory to their combustion for the production of heat. The invention contemplates a novel 20 form of hydrocarbon burner including a mixing chamber and an hydraulic pressure feed tank which may be attached to the service main of a city water system to cause the oil to be put under pressure so that it 25 will feed to the vaporizing chamber. The generic embodiment of the invention also comprises certain novel details of construction which are included in the preferred embodiment of the invention hereinafter 30 specifically described and illustrated in the accompanying drawings, in which:

Fig. 1, is a perspective view of hydrocarbon oil burning system, part of the pressure tank wall being broken away to illustrate 35 the interior thereof.

Fig. 2, is a vertical, longitudinal, sectional view through the burner and the mixing chamber, part of the vaporizing chamber being shown in the section.

40 Referring now to the drawings by numerals of reference:—

1 designates a tank, illustrated as a vertical, cylindrical tank closed at its respective ends. At the lower end of the tank is 45 a valved water inlet pipe 2 and a drain pipe 3. At the top of the tank is a valved oil inlet pipe 4, by means of which the hydrocarbon oil can be introduced into the tank from the top. 5 designates an air vent; extending from a point adjacent to the bottom of the tank 1, and projecting through the top is a pipe 6, controlled by a valve 6'. The pipe 6, communicates with a pipe 7, which extends through the top of the tank 50 a short distance as indicated at 8 and is controlled by a valve 9 between the pipe 6 and the tank 1. The pipe 7 communicates with a vaporizing tube 10 and is connected to the vaporizing tube by a coupling 11, in which is a valve 12. The vaporizing tube is in the 60 form of a split tubular ring, the split ends terminating in two tubular legs or extensions 13 and 14, the leg 13 being connected to the coupling 11. Leg 14 has a depending extension 15, carrying a nozzle 16, 65 adapted to be controlled by the valve 17. The nozzle is spaced from, but in axial alignment with a mixing chamber comprising a tubular body 18, considerably larger than the nozzle and into which the 70 nozzle discharges the hydrocarbon oil in the form of vapor gas. The mixing chamber 18 projects through a double wall burner cone having two perforate walls 19 and 20. The perforations 21, at the base of the conical 75 wall 20 admit the fuel mixture into the space 22, where the mixture may be admitted through the perforations 23. It will be observed that the perforations 21 are relatively large and are in circular series 80 near the base of the wall 20, while the perforations 23 extend entirely throughout the wall 19 so that the burning flame will be co-extensive with the cone. The cone supports a burner plate or disk 24, having a conical 85 recess 25, into which the apex of the cone is received and near the perimeter of the plate 24 are J-bolts 26, the curved ends of which engage the split ring shaped vaporizer 10. The double wall cone is preferably 90 formed of sheet metal and supported in a base pan 27, in which a suitable material 28, such as asbestos cement or the like may be placed to secure the cone to the pan. The pan is preferably imperforate so that all of 95 the air is supplied to the cone through the mixing chamber or tube 18. If desired, a priming tube or burner 29 may be associated with the burner to preliminarily heat the cone. Such burner may be connected to the 100 gas supply pipe and may have an arcuate end 30, following the curve of the burner cone as shown in Figure 1.

Assuming that the parts are properly assembled and that the oil has been introduced into the tank 1, the valve 31 in pipe 2, may be cracked so that water will flow into the tank, and since the specific gravity of oil is less than that of water, it is obvious that the oil will float on the column of water admitted to the tank. Since the water in all service pipes is under pressure, it will be 105 110

apparent that the oil will be put under pressure so that if the valve 9 is cracked and the valve 12 unseated, oil will flow into the vaporizing tube or chamber 10, and that if this tube has already been heated by a primer such as the burner 29, the oil will be vaporized or gasified; then if the valve 17 is open the vaporized oil will enter the mixing chamber 18 to combine with the air to provide a combustible fuel mixture which is introduced into the conical chamber 32 from which it will pass through the openings 21 into the space between the walls 19 and 20 of the cone and be emitted through the perforations 23, where it may be consumed. Having in mind that the pressure in the tank 1 will be equal in all directions, it is obvious that if the valve 6' in pipe 6 is unseated while the valve 9 is cracked, water will be admitted into the pipe 7, so that water and hydrocarbon oil can be fed to the vaporizing chamber, the hydrocarbon oil being converted into oil vapors and the water into water vapors, the two mixing or combining for whatever advantage there may be.

The introduction of the water however, is optional, as it may be entirely shut off from pipe 7 without affecting the feed of oil. If the valve 31 is left open the water will continue to enter the tank to take up the space vacated by the outgoing oil until finally the tank will be entirely full of water and have no oil in it. Then the valve 31 may be closed, the valved pipe 3 opened and water drained from the tank, a new charge of oil

may then be introduced into the tank through valved pipe 4.

What I claim and desire to secure by Letters-Patent is:—

1. An oil burner comprising a base pan, a double walled cone secured to the base pan, the inner wall of the cone having perforations near the base and the outer cone having perforations from the base to the apex, a mixing chamber extending through both walls of the cone, and means for discharging a hydrocarbon into the mixing chamber. 40

2. An oil burner comprising a double walled cone, the walls being in spaced relation to provide a conical chamber, the inner wall having perforations near its bottom and the outer wall having perforations at its apex, a mixing chamber extending through both walls of the cone and means for feeding hydrocarbon vapors to the mixing chamber. 50

3. An oil burner comprising a double walled cone, the walls of the cone being in spaced relation and having perforations, a mixing chamber extending through both walls of the cone, a plate carried at the apex of the cone, a substantially circular vaporizing chamber surrounding the cone, means for connecting the plate and vaporizing chamber, and means for feeding a hydrocarbon to the vaporizing chamber. 60

In testimony whereof I affix my signature.

AUBREY A. ADCOCK.
